UNITED STATES PATENT OFFICE

2,442,490

SHOE PLATFORM BEVELING MACHINE

Albert J. Germain, Haverhill, Mass., assignor to
 Albert J. Germain Company, Haverhill, Mass.,
 a corporation of Massachusetts

Application July 31, 1946, Serial No. 687,306

12 Claims. (Cl. 12—17)

1

This invention pertains to the manufacture of shoes of the so-called "platform" or California type, and more particularly to a machine for beveling the rear end of a forepart platform preparatory to its incorporation in the shoe, the present invention relating to improvements in the apparatus disclosed in the copending application of Hubert R. Smith, Serial No. 668,640, filed May 10, 1946.

The platform, mid-sole or cushion member of a platform shoe customarily terminates at the shank or adjacent to the heel breast line when the shoe is to have a high heel, the forepart platform being made from stock of substantially uniform thickness while the heel usually varies in height and may be considerably thicker than the forepart or platform proper. Where the platform meets the heel it is desirable to provide an overlap of these parts and to this end the platform is customarily beveled to fit the forward edge of the heel which is complementally beveled. The platform may be of substantial thickness, for instance, up to three-quarters of an inch or more, and is usually made of wood, sheet cork, felt or the like. Heretofore the beveling of the rear end of the platform has been done by hand, and since the material of the platform is resistant to cutting, by reason of its hardness or resilient nature, this hand operation is slow and laborious and can not be depended upon to produce uniform results.

The principal object of the invention is to provide improved work-holding means for positioning the platform and holding it securely at the proper angle for presentation to a beveling cutter or knife. A further object is to provide work-holding means for use in a power driven machine and operate securely to grip and to hold the work even though the material be of a nature which is difficult to cut. A further object is to provide work-holding means of simplified construction and which is easy to actuate both in securing the work in position and in releasing it. Other and further objects and advantages of the invention will be pointed out in the following more detailed description and by reference to the accompanying drawings wherein

Fig. 1 is a front elevation of a power driven machine equipped with the work-holding means of the present invention;

Fig. 2 is a plan view of the machine of Fig. 1 with parts broken away;

Fig. 3 is a fragmentary elevation showing the left-hand side of the improved work-holding means of the present invention with the parts in the position which they occupy while the

2

work-holding means is being engaged with the work;

Fig. 4 is a fragmentary elevation, to larger scale than Fig. 3, showing the right-hand side of the holding device, the work-supporting plate being broken away in part;

Fig. 5 is an elevation showing the left-hand sides of the pin-carrying slides of the work-holding device and showing the actuating cam in radial section;

Fig. 6 is a section substantially on the line 6—6 of Fig. 4; and

Fig. 7 is a section substantially on the line 7—7 of Fig. 2, showing a platform held in position in readiness to be beveled.

Referring to the drawings, the numeral 1 (Fig. 1) designates the base of the machine, which may be a casting and which has integral upstanding posts 2 and 3 near its right-hand edge. The base also has an upstanding supporting column 4 (Figs. 1 and 2) substantially mid-way between its front and rear edges and which is horizontally elongate transversely of the base and which is provided at its upper part with a horizontal bearing for the saw shaft hereinafter described.

The posts 2 and 3 have vertical axial bores which receive the vertically adjustable legs 5 and 6, respectively. These legs may be held in adjusted position by any suitable means, for example, set screws. The upper ends of these legs 5 and 6 are fixed in sockets in bosses 7 projecting downwardly from the underside of the table 9.

This table has a substantially flat and horizontal upper surface 10 and is provided with a dovetail slot 11 extending from its rear edge 12 to its forward edge 12^a. The table has a substantially vertical and smoothly finished rectilinear left-hand edge 14 extending from the rear edge 12 to the point 13, this edge being closely adjacent to the plane of action of the cutter blade. Forwardly of the point 13 the table is widened to provide the extension 15 which supports the work-clamping device.

This work-clamping device comprises a horizontal member 16 provided with parallel elongate slots 17 which receive screws having threaded shanks which enter threaded openings in the extension 15 of the table. The member 16 is thus adjustable transversely of the table and may be fixed in adjusted position. The clamping device also comprises the work-pressing plate 19 which is hinged to the member 16 at 20 to turn about a horizontal axis. The plate 19 is of some rigid material, for example metal, and is provided at

3

its upper edge with a handle 21, by means of which it may be swung about the hinge axis.

The work-supporting carriage comprises a rigid bottom plate 25 designed to rest on and to slide longitudinally of the table 9. This bottom plate 25 is provided with a downwardly directed key member 26 (Fig. 1) which fits and slides in the dove-tail slot 11 of the table. A work-supporting plate 29 is hinged to the bottom plate 25 at 27 to swing about a horizontal axis extending longitudinally of the table. The axes about which the plates 19 and 29 swing are relatively adjusted so that they are spaced apart a distance approximately equal to the thickness of the work-piece and are located at opposite sides of the plane of action of the cutter. The plate 29 is of rigid material, for example metal, and has a smooth flat upper or left-hand surface for engagement with the work. In order that the shoe platforms may be beveled to any of the angles required by the industry, the supporting plate 29 is desirably arranged, as here shown, to swing from a vertical position, where it is parallel to the plane of the cutting blade, through an arc of the order of 45° or more.

A screw 30 (Fig. 1) passes through an elongate slot 31 in a lever 32 pivoted at 33 to a bracket 34 mounted on the carriage 25. The screw 30 has threaded engagement with an opening in a bracket 35 fixed to the rear edge of the rear plate 29 near the top of the latter. By means of this screw 30, the plate 29 may be fixed at any desired angle of inclination to the plane of the table top.

The plate 29 has four rigid guides 35, 36; 37, 38 (Fig. 6) projecting from its under or right-hand side (Fig. 1) and arranged in the same vertical plane substantially mid-way between the front and rear edges of the plate 29. The guides 35, 36 are parallel and spaced apart and slope upwardly and to the right, as viewed in Fig. 6. The guides 37, 38 are parallel and spaced apart and slope downwardly and to the right as viewed in Fig. 6.

Two vertically slidable pin-carrying plates 39 and 40 are arranged at the right-hand or underside of the work-supporting plate 29. These plates have inclined bores 41, 42; 43, 44 (Fig. 5) for the reception of the guides 35, 36; and 37, 38. Interposed between the adjacent ends of the plates 39 and 40 is an axially elongate actuating cam 45 (Fig. 6). This cam is mounted to turn on a stub shaft 46a carried by the plate 29 and has an actuating handle 46 by means of which it may be turned. When this cam is turned a quarter turn from the position shown in Fig. 5, the plates 39 and 40 are thereby pushed apart to the maximum extent. In thus moving apart, the plates are constrained by the guides 35, 36; 37, 38 to move to the right, as viewed in Fig. 6, from the inactive, broken line position to the full line position where the plates 39 and 40 are in substantial contact with the underside of the plate 29.

The plates 39 and 40 are provided with vertical rows of sharp pointed pins or claws, the pins carried by the plate 39 being designated by the numeral 47, and those carried by the plate 40 by the numeral 48. As shown in Fig. 6, the pins 47 are straight and sloped upwardly and to the right, being parallel to the guides 35, 36, while the pins 48 are likewise straight and slope downwardly and to the right, being parallel to the guides 37, 38.

The plate 29 is provided with guide bores for the several pins 47 and 48. These bores are properly sloped to permit the pins to slide (as the

4

plates 39 and 40 move toward or from the plate 29). Preferably the guide bores for the pins 47 and 48 are of such dimensions as to receive the pins with a free sliding fit. However, it is contemplated that instead of individual bores for the several pins the plate 29 may have a vertical slot corresponding to each row of pins and which receives all of the pins of a given row.

The pins 47 and 48 are of such length and so arranged that when the plates 39 and 40 occupy the broken line positions shown in Fig. 6 the points of the pins are retracted within the substance of the plate 29, but when the plates 39 and 40 are positioned against the plate 29, the points of the pins project beyond the upper or work contacting surface of the latter.

Springs 49 and 50 urge the plates 39 and 40 toward each other and thus keep them in contact with the cam 45. The work-supporting plate 29 is preferably provided with a handle 51 (Fig. 2) projecting from its upper edge for convenience in adjusting it to the desired inclination and also to facilitate the operation of the clamping plate 19 as hereinafter described.

The bearing in the upper part of the support 4 of the base is designed to receive a rotary saw shaft 56 having the drive pulley 57 at its left-hand end and which is designed to receive a power driven belt. The opposite end of the shaft 56 is provided with means for attaching thereto a disk cutter, here shown as a circular saw blade 58. The parts are so arranged that the plane of this disk cutter is disposed very close to but out of contact with the finished vertical edge 14 of the table 9, the cutting edge being disposed rearwardly of the extension 15 of the table.

A shoe platform as above described is customarily made from stock of substantially uniform thickness; for instance, soft wood, felt, sheet cork or the like. The platform is died out from this material by a suitably shaped die so as to give it the desired peripheral contour, the rear edge of this blank, embryo platform, or workpiece thus produced usually being substantially straight. The rear edge portion of this workpiece or blank is of the same thickness as the remainder of the blank, and the purpose of the present apparatus is to form a bevel at the rear edge of this workpiece or blank.

Preparatory to the operation of the machine, the work-supporting member 29 is adjusted to an angle relatively to the plane of the upper surface 10 of the table 9 which is the complement of the desired angle of bevel, this adjustment being accomplished by loosening the nut 30 and swinging the plate 29 by means of the handle 51 to the desired position and then again tightening the screw 30. Assuming that the carriage is at the front of the machine and that the work-support 29 has been adjusted to the proper angle, the operator swings the handle 21 so as to turn the clamping member 19 outwardly to the left, away from the member 29 to some such position as shown in Fig. 1. He then places the work-piece F (Fig. 7) against the upper or left-hand surface of the member 29 with its lower edge approximately in the plane of the table top 10. The clamping member 19 does not move with the carriage. The lower edges of the parts 19 and 29 are spaced and so located that when the work-piece is operatively positioned its lower edge is in the plane of the cutting blade. The operator swings the handle 21 to the right, as viewed in Fig. 1, thus pressing the workpiece firmly against

75 the left-hand or upper face of the support 29.

When the clamping plate 19 has thus been positioned, the operator may grip both of the handles 21 and 51 in his left hand at the same time, and by exerting a squeezing or gripping pressure upon these handles he may very firmly press the workpiece between the plates 19 and 29. While thus holding the handles 21 and 51 with his left hand, the operator swings the handle 46 with his right hand, thus turning the cam 45 so as to move the plates 29 and 30 in opposite directions. The pins 47 and 48 are thus projected through the guide openings in the plate 29 and into the substance of the workpiece P, which is firmly supported in opposition to the thrust of the pins by the rigid plate 19 overlying it. Since the pins carried by the plates 39 and 40, respectively, slope in opposite directions they have a claw action, exerting a talon-like grip upon the workpiece when projected into the latter, thus firmly holding the workpiece to the support 29. The operator now releases the clamping plate 19 and preferably swings it to the left and away from the plate 29, thus fully exposing the upper surface of the workpiece so that the operator has a clear view of the workpiece during the cutting operation. The operator now pushes the carriage 25 rearwardly, while leaving the handle 46 in the position to which it has been moved, and as the carriage is moved rearwardly the blade 58 passes through the entire width of the workpiece P, thus slicing off a triangular block at the lower corner of the workpiece and providing the desired bevel. The carriage is now returned to the front of the machine and the handle 47 is restored to its initial position, thus retracting the pins from the workpiece and freeing the latter for removal from the supporting plate 29. If preferred, the workpiece may be released from the plate 29 before the carriage is returned to the front of the machine. Obviously by adjusting the support 29 to other angles, the angle of the bevel will be correspondingly changed. It is thus possible to bevel the platform to correspond to any type of heel and to obtain substantially uniform results without requiring any particular skill or care on the part of the operator.

By reason of the firm talon-like grip or claw action which the pins provide, the workpiece is very firmly held to the support 29 without requiring any effort on the part of the operator to hold it in place during the actual cutting operation; thus it is not necessary for the operator to lean over the saw during the beveling operation, nor is there any danger that the workpiece will slip during the operation by reason of any failure of the operator to exert the necessary pressure or force to keep the workpiece in place.

Moreover, by reason of this novel means of attaching the workpiece to the support, it is possible to operate upon workpieces of any desired shape or material which may be employed for making a shoe platform with the assurance that the workpiece will be properly held at the desired position and angle for the beveling operation.

While one desirable embodiment of the invention has been illustrated by way of example, it is to be understood that the invention is broadly inclusive of any and all modifications falling within the scope of the appended claims.

I claim:

1. Apparatus for use in beveling the rear edge of a shoe platform, said apparatus comprising a rotary disk cutter, a carriage movable in a path parallel to the plane of the cutter, an adjustable

work support mounted on the carriage to swing about an axis parallel to the path of the carriage, work-attaching elements carried by the work support, and cam means operative to engage said elements with the workpiece.

2. Apparatus for use in beveling the rear edge of a shoe platform, said apparatus comprising a rotary disk cutter, a carriage movable in a path parallel to the plane of the cutter, a support 10 mounted on the carriage, means operative temporarily to clamp a workpiece to the support, work-attaching elements carried by the support, and means for operatively engaging said attaching elements with the workpiece while the latter is temporarily clamped to the support.

3. Apparatus for use in beveling the rear edge of a shoe platform, said apparatus comprising a cutter, a carriage movable in a path parallel to the plane of action of the cutter, a work support 20 mounted on the carriage, a clamping plate operative to hold a workpiece temporarily in firm engagement with the support, work-penetrating attaching elements having points normally housed within the substance of the support, and 25 means for projecting said points into a workpiece held between the clamping plate and the support.

4. Apparatus for use in beveling the rear edge of a shoe platform, said apparatus comprising a cutter, a carriage movable in a path parallel 30 to the plane of action of the cutter, a work support mounted on the carriage, the support having a plurality of guide bores therein, work-attaching claws 35 slideable in said bores, and means operative simultaneously to advance said claws into holding relation to a workpiece on the support.

5. Apparatus for use in beveling the rear edge of a shoe platform, said apparatus comprising a rotary disk cutter, a carriage movable in a path parallel to the plane of the cutter, a work support 40 mounted on the carriage, the support having a plurality of guide bores therein, two sets of attaching pins disposed to slide in said bores, one set of pins being inclined oppositely to those of the other set, and means operative 45 to advance all of said pins into a workpiece mounted on the support.

6. Apparatus for use in beveling the rear edge of a shoe platform, said apparatus comprising a cutter, a carriage movable in a path parallel 50 to the plane of action of the cutter, a work support mounted on the carriage, the support having a plurality of apertures therein, inclined guides fixed to the support, pin-carrying plates slideable parallel to said support, said plates having bores 55 which receive said guides, said plates carrying attaching pins which extend through the apertures in the support, and means operative to move the plates in opposite directions, to cause them to move toward the support and thereby 60 protrude the attaching pins into a workpiece mounted on the support.

7. Apparatus for use in beveling the rear edge of a shoe platform, said apparatus comprising a rotary disk cutter, a carriage movable in a path 65 parallel to the plane of the cutter, a work support mounted on the carriage, the support having two sets of guide apertures therein, a set of work-attaching pins disposed in each respective 70 set of apertures, two plates parallel to the support, each plate carrying one of said sets of pins, respectively, means so guiding the plates that force applied to the plates in a direction parallel to the support causes them to move bodily toward and from the support, a cam operative to 75

apply such force to the plates thereby to separate them, and springs urging the plates toward each other.

8. Apparatus for use in beveling shoe platforms comprising a stationary table, a rotary disk cutter, a carriage supported by the table, means guiding the carriage to move in a path parallel to the plane of the cutter, a work support hinged to the carriage to swing about an axis parallel to the path of the carriage, work-attaching claws carried by the support, means for projecting the claws into a workpiece resting upon the support, and means operative to hold the workpiece against the support while the claws are being engaged with the workpiece.

9. Apparatus for use in beveling shoe platforms comprising a stationary table, a cutter, a carriage supported by the table, means guiding the carriage to move in a path parallel to the plane of action of the cutter, a work support mounted on the carriage, two series of oppositely inclined attaching pins arranged to slide in corresponding bores in the support, means operative simultaneously to project the pins of the two sets into a workpiece resting on the support, and means operative to hold the workpiece in firm engagement with the support while the pins are being engaged with the workpiece.

10. Apparatus for use in beveling shoe platforms comprising a stationary table, a rotary disk cutter, a carriage supported by the table, means guiding the carriage to move in a path parallel to the plane of the cutter, an adjustable work support hinged to the carriage to swing about an axis parallel to the path of the carriage, a work-clamping member arranged to swing about an axis parallel to that about which the support swings, said axes being disposed, respectively, at opposite sides of the plane of the cutter blade and being spaced apart a distance approximating the thickness of the workpiece, the clamping means and support having handles which are juxtaposed when the clamping means is in operative position so that they may both be grasped by the operator's hand and urged toward each other, work-attaching means carried by the support, and means for operatively engaging said attaching means with a workpiece held between the clamping member and support.

11. Apparatus for use in beveling shoe plat-

forms comprising a stationary table, a rotary disk cutter, a carriage supported by the table, means guiding the carriage to move in a path parallel to the plane of the cutter, an adjustable work support hinged to the carriage to swing about an axis parallel to the path of the carriage, a work-clamping member arranged to swing about an axis parallel to that about which the support swings, said axes being disposed, respectively, at opposite sides of the plane of the cutter blade, means whereby the clamping member may be urged toward the support by the use of one hand, and means actuatable by the other hand for attaching the workpiece to the support.

15. 12. Apparatus for use in beveling shoe platforms comprising a stationary table, a rotary disk cutter, a carriage supported by the table, means guiding the carriage to move in a path parallel to the plane of the cutter, an adjustable work support hinged to the carriage to swing about an axis parallel to the path of the carriage, a work-clamping member arranged to swing about an axis parallel to that about which the support swings, said axes being disposed, respectively, at opposite sides of the plane of the cutter blade, handles projecting from the upper parts of the clamping member and support, respectively, said handles being so relatively disposed, when the clamping member is in operative position, that they may be grasped in one hand and urged toward each other by the grip of the hand, thereby firmly holding a workpiece interposed between the clamping member and support, work-attaching claws arranged to project through openings in the support and into the workpiece, a cam for projecting the claws, and a handle actuatable by the other hand of the operator for operating the cam.
